UNITED STATES PATENT OFFICE

ROBERT DRURY MARTIN, OF JACKSONVILLE, TEXAS

WELL-DRILLING BIT

Application filed October 21, 1929. Serial No. 401,154.

The invention aims to provide a new and improved well drilling bit which may be easily and inexpensively manufactured and will possess adequate provision for supplying water to prevent gumbo and the like from clinging to said bit.

With the foregoing in view, the invention resides in the novel subject matter hereinafter described and claimed, description being accomplished by reference to the accompanying drawing.

Fig. 1 is a partly disassembled perspective view of one form of the invention.

Fig. 2 is a vertical sectional view thereof.
15 Fig. 3 is a partly disassembled perspective showing a modification.

Figs. 4, 5 and 6 are views similar to preceding figures but showing a still further modification.

20 In Figs. 1 to 2, the numeral 10 denotes a cylindrical head having an integral upstanding driving neck 11 for engagement with the usual driving and water feeding tube. Integral with and projecting downwardly from the head 10 is a substantially flat blade 12 whose lower end is provided with oppositely turned bits 13, opposite sides of said blade being centrally grooved at 14 to permit easy longitudinal slitting and bending of the blade 25 upon heating, when the bits 13 have become worn away to such an extent to require the formation of new bits. Two longitudinal water ports 15 are formed through the neck 11 and the head 10, the lower ends of said ports being in communication with the upper ends of the grooves 14.

A rib-forming block 16 is welded transversely across each side of the blade 12 and is provided with a lug 17 received in the groove 14 to form a barrier across the latter. The inner edge of each block 16 is provided with notches 18 from the upper to the lower side of said block, constituting water discharge ports over the bits 13. Two arcuate cover plates 19 are welded at their upper edges to the periphery of the head 10, are welded at their lower edges to the blocks 16, and are welded at their ends to the longitudinal edges of the blade 12, thereby providing two water chambers 20 disposed at op-

posite sides of the blade. Water is supplied to these chambers through the ports 15 and is discharged from them through the notches or ports 18, giving the necessary supply of water to the drilling bits to obtain the best 55 results.

The present device is somewhat similar to that shown in my U. S. Patent No. 1,211,331 of January 2, 1917, but due to the novel manner of constructing the tool, it may be manufactured much more easily and less expen-

sively.

In Fig. 3, the characters 10^a to 20^a correspond with the structural formations indicated by the numbers 10 and 20 in the form 65 of construction first described. It will be observed however that whereas in the first form of the invention, two water chambers 20 are provided at opposite sides of the blade 12, and each block 16 is formed with two ports 18, Fig. 3 discloses only one water chamber 20^a and only one water discharge port 18^a. This construction may be used if desired and it will also be understood that it may be duplicated in some instances at the opposite side 70 of the blade 12^a.

In Figs. 4, 5 and 6, the characters 10^b to 15^b denote formations identical with the formations above denoted by the numbers 10 to 15. The water chambers 20^b however are formed differently. Two curved metal plates 19^b are welded against opposite sides of the blade 12^b and to the lower end of the head 10^b, said plates having portions 16^b forming the bottoms of the chambers 20^b. These portions 80 85 16^b are provided with lugs 17^b closing the grooves 14^b, and are formed with notches 18^b for discharging water. There may be only one plate 19^b and one port 15^b employed if desired and regardless of the number of these plates used, each may have either one or two notches such as 18^b.

On account of the existing advantages for the details disclosed, they are preferably followed. However, within the scope of the invention as claimed, minor variations may be made.

I claim:

1. A well drilling bit comprising a cylindrical head, a driving neck coaxial with said

head and projecting upwardly therefrom, a blade projecting downwardly from said head and having oppositely turned bits at its lower end, said head and neck having a water port from the upper end of the neck to the lower end of the head and open at one side of said blade, and metal casing means welded to one side of said blade and to the lower end of said head, forming therewith a water chamber communicating with said port, the bottom portion of said casing means having a water discharge opening.

2. A structure as specified in claim 1; said blade side having a longitudinal groove, said bottom portion having an integral lug closing said groove.

3. A well drilling bit comprising a cylindrical head, a driving neck coaxial with said head and projecting upwardly therefrom, a blade projecting downwardly from said head and having oppositely turned bits at its lower end, said head and neck having a water port from the upper end of the neck to the lower end of the head and open at one side of said blade, a transverse rib extending across said one side of said blade near the upper end thereof, said rib having a water discharge port from its upper to its lower side, and an arcuate covering plate secured at its upper edge to the periphery of said head, secured at its lower edge to said rib, and secured at its ends to longitudinal edge portions of the blade, thereby providing a water chamber for supplying water to said bits.

4. A well drilling bit comprising a cylindrical head, a driving neck coaxial with and projecting upwardly from said head, a blade projecting downwardly from said head, said blade having oppositely turned bits at its lower end and a central longitudinal groove in at least one of its sides, said neck and head having a water conducting port opening into the upper end of said groove; a transverse block welded across one side of said blade near the upper end of the latter and having a lug received in said groove to form a barrier across the latter, the inner edge of said block having a water conducting notch spaced toward one of its ends from said lug, and an arcuate covering plate welded at its upper edge to said head, welded at its lower edge to said block, and welded at its ends to longitudinal edge portions of said blade, providing a water chamber for supplying water to said bits.

In testimony whereof I have hereunto affixed my signature.

ROBERT DRURY MARTIN.
